UNITED STATES PATENT OFFICE.

ADAM E. SCHATZ, OF MOUNT VERNON, NEW YORK.

SHOE FOR FURNITURE-LEGS.

1,106,520.

Specification of Letters Patent. Patented Aug. 11, 1914.

Application filed May 5, 1911. Serial No. 625,375

To all whom it may concern:

Be it known that I, ADAM E. SCHATZ, of Mount Vernon, in the county of Westchester and State of New York, have invented certain new and useful Improvements in Shoes for Furniture-Legs, whereof the following is a specification, reference being had to the accompanying drawings.

The object of the invention is to provide a simple and inexpensive device of the character indicated, which may be easily applied to the legs of chairs or other articles of furniture, and which when once applied is so securely attached to the same as not to subsequently become detached therefrom.

The shoe is formed by stamping-up a disk of sheet metal into a convexity which forms the sliding surface of the shoe. Around the edge of the convex portion and at right angles to its sliding surface are formed three or more flattened prongs with side spurs near their points. By properly spacing these flattened prongs around the edge of the convex body of the shoe such variation in the planes of the prongs is obtained as insures the proper embedding of one or more of them into the wood, with such firm engagement of the spur in the wood as to prevent subsequent detachment.

In the accompanying drawings, Figure I, is a perspective view of a shoe embodying my invention. Fig. II, is a similar view, with parts broken away, showing the shoe as applied to the end of the leg of the piece of furniture, such as a chair. Fig. III, is a cross section on the line III, III, Fig. II, illustrating the way in which the prongs, or some of them, attach themselves within the wood at the end of the furniture leg.

The body of the shoe is stamped-up from a piece of sheet metal so as to take the form of a convex disk 1, the center of its convexity forming the sliding surface of the shoe. Around the rim of this convex disk, integrally with it, and projecting at right angles to the sliding surface of the shoe are formed flattened prongs 2, 2, 2. For reasons which will hereinafter be made clear, there should be not less than three of these prongs. Each prong is pointed and provided with opposed side spurs 3, 3, forming a spear head at the end of the prong. These spear headed flattened prongs being preferably three in num-

ber and spaced equi-distantly around the rim of the convexed disk necessarily lie in different planes, related to each other as the sides of an equilateral triangle. The purpose of the spurs on the sides of the prongs is to hold the prong, when driven into the wood, from becoming subsequently detached therefrom, which accident the prongs prevent by embedding themselves in the wood, which by its natural resiliency surrounds and takes hold upon the point of each spur. As these shoes are intended for the ends of the leg of a piece of furniture, which in almost all cases is cross cut to the grain of the wood, it is obvious that the flattened prongs must enter the wood in the direction of its grain. As shown in Fig. III, the grain of the wood under these circumstances presents the appearance of more or less concentric layers surrounding a center which except in very rare instances, will never be the center of the furniture leg. If a flattened prong, whether provided with spurs or not, is inserted into a cross cut wooden surface in such a way that the plane of the flattened prong coincides with the dividing plane between two of the concentric layers forming the wood, the tendency of the prong is to cleanly divide the two layers from each other, and the resiliency of the wood under these circumstances is not sufficient to thereafter completely embed the spurs formed on the edges of the flattened prong, for the separation of the layers of the wood projects slightly beyond the sides of the prong as shown at 5, in Fig. III. But if the same flattened prong be driven into the same piece of wood in such a way that its plane is in angular relation to the layers of the wood, the resiliency of the wood is much greater, and spurs formed on the sides of the prongs are embedded and firmly caught, as shown at 6, 6, in Fig. III. By providing the shoe with three or more of these flattened prongs in different planes, it is insured that one or more of the prongs will so enter the wood as to enable the spurs to properly embed themselves to prevent the detachment of the shoe.

Having thus described my invention, I claim:

As a new article of manufacture, a sliding shoe for furniture legs, comprising a

body portion stamped-up from a metal blank in the form of a convexed disk; three or more equidistant integral flattened prongs projecting from the rim of the disk at right angles to its center of convexity; and opposed side spurs near the point of each prong, substantially as described.

In testimony whereof, I have hereunto signed my name at Philadelphia, Pennsylvania, this third day of May, 1911.

ADAM E. SCHATZ.
